UNITED STATES PATENT OFFICE.

THOMAS SPENCER MILLER, OF SOUTH ORANGE, AND JOSEPH H. DICKINSON, OF MONT-
CLAIR, NEW JERSEY.

LOGGING APPARATUS.

Application filed August 2, 1922. Serial No. 579,141.

To all whom it may concern:

Be it known that we, THOMAS SPENCER MILLER and JOSEPH H. DICKINSON, citizens of the United States, and residents of South Orange, in the county of Essex and State of New Jersey, and Montclair, in the county of Essex and State of New Jersey, respectively, have invented certain new and useful Improvements in Logging Apparatus, of which the following is a specification.

Our invention relates to new and useful improvements in logging apparatus of that character or type embodying a car or platform supported on running wheels adapted to travel on track rails, which platform supports logging means by which logs are hauled, decked, etc.

In Patent No. 914,441, already granted to us, is disclosed a logging apparatus embodying a single platform mounted on wheeled trucks, and carrying at each end an elevated structure, over which pass log-hauling lines operated by independent engines supplied with steam from a single boiler. The structure just described has certain practical objections. For example, with the single car platform it is necessary to have a rigid platform as long as 40 feet in order to carry the engines and a boiler of the necessary size, and to have the ends of the platform overhang the trucks in order to provide room for the masts or booms. The overhanging ends under the strains of logging act as a spring-board, which results in the gears and bearings being thrown out of proper mesh and alinement. Again, the lines passing over the two skidding booms fixed to one platform, frequently are operated in opposite directions, thus producing serious twists, loosening the foundation bolts and resulting in a destructive effect on the platform and engine.

The primary object of our present invention is to provide a structure by which the objections heretofore mentioned are obviated, and to this end, the invention consists in the improvements to be more fully described hereinafter and the novelty of which will be particularly pointed out and distinctly claimed.

We have fully and clearly illustrated our invention in the accompanying drawings, to be taken as a part of this specification, and wherein Figure 1 is a view, in side elevation, of a structure embodying our inven-

tion; Fig. 2 is a plan view of the structure shown in Fig. 1; Fig. 3 is a view, in side elevation, partly in section, of a propelling means, and Fig. 4 is a diagrammatic plan view of a portion of the structure shown in Fig. 3.

Referring to the drawings by characters of reference, 1, 2 designate, respectively, two platforms, each of which embodies a horizontal member of any construction suitable for the purpose. These platforms are preferably oblong in plan and arranged end to end, as clearly shown. Each of these platforms is supported on wheeled trucks 3, preferably of the four-wheeled type, the bolster 4 of the outer end of each truck being arranged under the portion of the platform directly under the skidding boom end, so that the load is distributed on the platforms between the points of support on the trucks. The wheels of the trucks are adapted to travel on suitable track rails 5.

The inner ends of the platforms are flexibly connected by a suitable joint or coupling 6, which may be of any well known form which will permit a relative movement between the platforms, either laterally or vertically, and will permit one to rock or twist without communicating such movement to the other. In the form shown, the coupling comprises interengaging plates 6^a secured to the respective platforms, the plates being pivotally connected together by a pin 6^b, it being understood that sufficient play between the parts is provided to provide the relative movement above referred to. The coupling may, if desired, be of a more or less permanent character, as shown, as it is unnecessary to uncouple the platforms under usual conditions.

At the outer end of each platform, and preferably over the truck bolster 4, is pivoted, as at 7, an elevated structure in the form of an A-boom 8, at the upper end of which is pivoted, as at 9, a swinging block 100 frame or stub-boom 10, to which is hung, in any suitable manner, a plurality of sheaves, including oppositely disposed skidding sheaves 11, over which pass skidding lines 12, wound on drums 13 of an engine 14 supported on the platform adjacent the base of the boom 8. The engines 14 may be of any suitable type known in the art for logging purposes, for example, the "Lidgerwood," and need not be described in detail here.

Each boom may also have hung thereto sheaves 15 over which pass guy lines 16, the outer ends of which are connected to points of the platform, for example, to stumps, 5 while the inner ends are wound on guy drums 17 operated by the engine 14 in a well known manner.

On the platform 2 is arranged a steam boiler 18 of any suitable type to supply steam 10 to the cylinders 14^a of the engines 14. The boiler is connected by a pipe 19 with the throttle (not shown) of the engine on platform 2, and said boiler is provided with a pipe 20 connected by a flexible hose 21 to a 15 pipe 22 leading to the throttle (not shown) of the other engine. The boiler is preferably located adjacent the inner end of the platform 2.

On the platform 1, adjacent the inner end 20 thereof, is a water tank 23, to contain the water supply for the boiler.

By the construction described, we are able to employ a duplex logging apparatus, and supply the engines for the same with the necessary steam, and, at the same time, provide a structure in which the strains to which one logging apparatus is subjected will not be communicated to the other, this advantage arising from the employment of a flexible joint or coupling between the platforms.

By employing two flexibly connected platforms, we are, in fact, enabled to employ a longer total length than heretofore, which affords ample space for supporting the various elements of the logging apparatus, for example, each of the platforms may be twenty-five feet in length, making an approximate over-all length of fifty feet, but, at the same time, the apparatus will easily 40 accommodate itself to inequalities in the road-bed and to curves in the track.

A further advantage resides in the fact that the platforms may each be supported on two four-wheeled trucks, which assures a 45 more even distribution of the total load upon the wheels and the trackway than is possible where it is necessary to support the entire load on a single platform resting on two six-wheeled trucks.

50 We may, if desired, propel the improved apparatus by driving the truck wheels on one of the platforms from the engine on that platform. The engine includes a gear 24 carrying a sprocket 25 connected by a chain 55 26 to a sprocket 27 fast on a shaft 28 extending transversely of the platform at a point between the trucks, a similar shaft 28^a preferably being located adjacent to said shaft

28 and connected thereto through gears 29. Sleeves 29^a and 29^b are loosely mounted on 60 the respective shafts, and are operated therefrom through suitable clutch members 30^a and 30^b. By operating one clutch member or the other the vehicle may be propelled in either direction, as is obvious, the arrangement being particularly useful where a non-reversible engine is used. It will, of course, be understood that suitable coupling members are interposed between the engine and the car propulsion means, so that the latter may be connected and disconnected at will. The same constitutes no part of our present invention and, for that reason, we have not illustrated the same.

What we claim and desire to secure by 75 Letters Patent of the United States is:

1. A log skidding apparatus comprising platforms arranged end to end and flexibly connected together, wheeled trucks supporting the ends of each of said platforms and adapted to travel on track rails, a skidding structure mounted on the outer end of each platform, a skidding engine associated with each skidding structure at the same end of the platform, a logging line extending from each engine over the associated skidding structure, and a steam boiler mounted on the inner end portion of one of said platforms and connections for supplying steam from said boiler to each of said engines, the load mounted on said trucks being distributed between the points of support of said trucks.

2. A log skidding apparatus comprising platforms arranged end to end and flexibly connected together, wheeled trucks supporting the ends of each of said platforms and adapted to travel on track rails, an elevated skidding structure mounted on the outer end of each platform, a skidding engine associated with each skidding structure at the same end of the platform, a logging line extending from each engine over the associated skidding structure, and a steam boiler mounted on the inner end portion of one of said platforms and connections for supplying steam from said boiler to each of said engines, the load mounted on said trucks being distributed between the points of support of said trucks.

THOMAS SPENCER MILLER.
JOSEPH H. DICKINSON.
